UNITED STATES PATENT OFFICE.

BERNARD ARTHUR BEHREND, OF NORWOOD, OHIO, ASSIGNOR TO ALLIS-CHALMERS COMPANY, A CORPORATION OF NEW JERSEY, AND THE BULLOCK ELECTRIC MANUFACTURING COMPANY, A CORPORATION OF OHIO.

DYNAMO-ELECTRIC MACHINE.

No. 926,086.

Specification of Letters Patent.

Patented June 22, 1909.

Application filed August 21, 1905. Serial No. 275,118.

To all whom it may concern:

Be it known that I, BERNARD A. BEHREND, citizen of the United States, residing at Norwood, in the county of Hamilton and State 5 of Ohio, have invented certain new and useful Improvements in Dynamo-Electric Machines, of which the following is a full, clear, and exact specification.

My present invention relates to improvements in the construction of dynamo-electric machines, particularly high-speed turbo-generators and the means for ventilating the same.

In the types of dynamo-electric machines, 15 especially the high-speed machines employed at the present time, the rotary member is provided with connecting axial and radial passageways and the stationary member is provided with radial passageways, which 20 communicate through the air-gap of the machine with the radial passageways in the rotary member. The passageways are so arranged that when the machine is in operation, the ventilating currents of air enter the 25 rotary member through the said axial passageways, then flow through the radial passageways of said member into the air-gap separating the rotary and stationary members, thence through the radial air-gaps of 30 the stationary member and out of the machine through openings in the periphery of its frame or yoke. In high-speed machines and particularly in turbo-generators, it is difficult with the construction just described 35 to force sufficient air across the air-gap to ventilate the stationary member, and in addition it has been found by experience that the volume of air passing through the machine in a radial direction is not evenly distributed across the length of the machine. 40 On the contrary it has been found that a much greater volume of air passes with a much greater velocity radially outward near the middle of the machine than near the 45 ends of the machine, the volume and velocity decreasing gradually from the middle to the ends.

The object of my invention is to so construct a dynamo-electric machine and arrange 50 the ventilating passageways in such a manner that good and uniform ventilation is secured at all parts of the machine.

In carrying out my invention, I provide

a rotatable member of a dynamo-electric machine having communicating radial and 55 axial passageways, with enlarged radial passageways at the middle, so that a much greater volume of air will flow therethrough than through the other radial passageways.

My invention further consists of a stationary member of a dynamo-electric machine having circumferential passageways, and at its middle an enlarged circumferential passageway communicating with the first named passageways, whereby, when the machine is in operation, a large volume of air will be received into the enlarged passageway and conveyed to the first named smaller passageways.

My invention still further consists of a 70 dynamo-electric machine having a stationary member and a rotatable member, the latter being provided at its middle with means for cooling the stationary member.

Considering my invention more specifically, I provide the rotary member with a comparatively large spacing member having radial fan blades. The stationary member is provided at intervals with circumferential passageways which preferably do not 75 communicate with the air-gap of the machine. The stationary member is further provided with a wide circumferential passageway or conduit directly opposite or surrounding said spacing member, or rotor fan. 80 This large passageway receives from the rotor fan the ventilating currents of air which pass into a receiving chamber preferably extending the full length of the machine, and communicating with the circumferential passageways in the stationary member. The frame is provided with openings for the escape of the air after same has 85 passed through said circumferential passageways.

My invention further consists in the details of construction and combinations of parts more fully set forth in the following description and in the appended claims.

Referring to the drawings which illustrate 100 the preferred embodiments of my invention, Figure 1 is a sectional elevation of an ordinary form of turbo-generator rotor construction, the lengths of the arrows indicate approximately the relative volumes or 105 velocities of the air escaping from the rotor

during rotation; Fig. 2 is a sectional elevation of the rotor and stator of my improved machine, the arrows showing the directions of the currents of air through the various air passages; Fig. 3 is a similar view of the rotor of Fig. 2, removed from the stator, the lengths of the arrows in the various air passages indicating approximately the relative volumes and velocities of air passing therethrough; Fig. 4 is a section taken along the line 4—4 of Fig. 2; Fig. 5 is a section taken along the line 5—5 of Fig. 2; Fig. 6 is a sectional elevation of a modified form of my invention; Fig. 7 is a section 15 along the line 7—7 of Fig. 6; and Figs. 8 and 9 are sections on reduced scale along the lines 8—8 and 9—9 respectively of Fig. 6.

Referring more specifically to the figures, in Fig. 1 I have shown at A, an ordinary form of turbo-generator rotating field provided with the axial air passages 1 and the radial air passages 2. By the fan-like action of the rotor, air is drawn into the axial air passages and forced radially outward through the radial passages. The lengths of the arrows extending from each of the radial passageways indicate approximately the relative volumes and velocities of the air thus forced outwardly. It will be seen that a much greater volume of air passes with a greater velocity radially outward near the middle of the machine than near the ends, the volume and velocity decreasing gradually from the middle to the ends. In my improved machines I utilize this phenomenon by assisting the greater flow of air at the middle of the rotor and by directing the air currents from the middle of the rotor to a receiving chamber from which the currents pass uniformly through all parts of the stationary member.

In the preferred form of my invention illustrated in Figs. 2, 3, 4, and 5, A¹ represents the rotary field structure, which is built up of groups of laminæ 3 mounted on the shaft 4 in the usual manner, between the end heads 5, 5, the end heads being held on the shaft by the nuts 6, 6. The end heads and laminæ are provided with axial air passages 7 communicating with radial air passages 8 also in the usual manner. In the middle of the rotor I separate the two groups of laminæ by a comparatively large spacing member 9 preferably provided with radial fan blades which when the rotor is in motion force the major part of the air to the middle of the rotor and expel it radially outward. The stator core B¹ is in this case the armature. I wish it understood, however, that my invention is applicable to a stationary field member and rotating armature as well. The stator core consists of bundles or groups of laminæ 10, dove-tailed to the frame 11 and held between end heads 12. The groups of laminæ are

spaced apart and form circumferential ventilating passages 13. These ventilating passages preferably do not communicate with the air-gap of the machine as is customary, but in the preferred forms shown are provided with strips or plugs 14 which close completely the passages in the inner periphery. For the sake of clearness the windings have been omitted from both the stationary and rotary members. At the middle of the core of the stationary member, I have provided a large circumferential passageway or conduit 15 directly opposite the central fan of the rotary member, to receive the air from the said fan. At the lower part of this passageway 15 I have arranged a barrier 16 to direct the air into the chamber 17 at the bottom of the machine, said chamber preferably extending the full length of the machine and communicating with all the circumferential ventilating slots between the groups of laminæ. At the top of the machine or at any other desired point the frame is provided with openings 18 for the escape of the air currents, the air passing upwardly on both sides of the rotor, as shown by the arrows in Fig. 5. It is seen that in this form of the machine the stationary member is well ventilated, there being nothing to hinder the free circulation of air. Likewise the air passes upward from the chamber 17 uniformly through all the passageways. Also by this construction and arrangement of air passageways and by preventing direct communication between the radial passageways in the rotor and the passageways 13 of the stationary member, the troublesome and annoying humming noise is in a great measure abated.

In Figs. 6, 7, 8, and 9, I have shown a modification of my invention. Instead of ventilating the entire machine by the central fan 9 on the rotary member, I arrange on each end of the rotary members radial fan blades 19. The central fan blades, as in the construction previously described draw the air through the axial passages of the rotary members. A part of these air currents pass through the narrower circumferential slots into the air-gap and is then forced by the fan into the large circumferential air-gap 20 in the stationary member. This air-gap 20 is constructed somewhat differently than in the other constructions. The air currents instead of passing into a large chamber at the bottom of the machine pass directly out through openings 21, two barriers 22 being here shown, although it is obvious that a single barrier and a single passageway for the escape of the air would be sufficient.

The ventilation through the core of the stationary member is obtained from a source entirely separate from that which ventilates the rotary field. In this case the air pas-

sages in one part communicate in no manner with the air passages in the other part. The fan blades on the ends of the stationary member force the air into the two circumferential air passages 23, 23 in the end members by passages 24. From these passages 23 the air is directed by the barriers 25 into two receptacles 26, 26 at each side and at the bottom of the machine. These two receptacles 26, 26 communicate with all the narrow circumferential air slots in the stationary member, through which the air passes upward on both sides of the rotor and escapes by the passages 27, 27.

15 Having thus described my invention, what I claim as new and desire to secure by Letters Patent is—

1. In a dynamo-electric machine, a stationary member provided with circumferential ventilating passageways, and with a chamber communicating with all said passageways a rotatable member, means located at the middle of said rotatable member for forcing air into said chamber and thence through the circumferential passageways of the stationary member to cool the latter.

2. An annular stationary member for a dynamo-electric machine having circumferential air passageways closed at the inner periphery and at its middle an enlarged circumferential air passageway open at the inner periphery and communicating with said first named circumferential passageways.

3. A stationary member for a dynamo-electric machine comprising a laminated core and a surrounding field frame, said core having a plurality of circumferential air passageways, and being divided at the middle in two parts which are spaced apart forming with the surrounding field frame an annular air chamber which is open at the inner periphery of the core and closed by the frame at the outer periphery thereof, an air chamber or passageway communicating with said annular chamber and with all said circumferential passageways whereby air may be conducted from the former to the latter.

4. In a dynamo-electric machine, a rotatable member provided with axial ventilating passageways and at the middle with means for creating a good outward circulation of air, a stationary member comprising a laminated core and a surrounding field member, said core having circumferential air passageways and being divided at the middle in two parts, which are spaced apart forming with the surrounding field frame an annular chamber open at the inner periphery of the core and closed at the outer periphery, and a chamber leading from said annular chamber to said circumferential passageways, whereby air may be forced by

the rotatable member into the annular chamber, thence into said second named chamber, and thence through said circumferential passageways.

5. In a dynamo-electric machine, a rotatable member having axial ventilating passageways, a stationary member consisting of a laminated core and a surrounding field frame, said core having circumferential ventilating passageways and at the middle an annular chamber open at the inner periphery of the core and closed by the field frame at the outer periphery of the core, said frame having at one side of the core an air receiving chamber communicating with said annular chamber and with said circumferential passageways and said frame having at the side of the core opposite from said air receiving chamber exhaust openings, and means at the middle of said rotatable member for forcing air into said annular chamber, thence into the air receiving chamber, and thence through the circumferential passageways in the core to the exhaust openings in the frame.

6. In a dynamo-electric machine, a rotatable member provided with radial and axial ventilating passages, a fan at the middle of said member, a stationary member provided with ventilating passages, a frame surrounding said stationary member, said stationary member being divided into two substantially equal parts which are spaced apart forming with the outer surrounding frame a circumferential chamber surrounding the fan, whereby the ventilation through the rotatable member and between the stationary and rotatable members is enhanced, and means for directing air through the passages in the stationary member.

7. In a dynamo-electric machine, a rotatable member having at the middle means for creating a good outward circulation of air, a stationary member comprising an annular core and surrounding frame, said core having spaced circumferential passageways closed at the inner periphery and having at the middle a comparatively large passageway or annular chamber open at its inner periphery, and means for conducting air from said annular chamber to said circumferential passageways.

8. In a dynamo-electric machine, a rotatable member having at the middle thereof means for creating a good outward circulation of air, and a stationary member consisting of an annular core and a frame, said core having spaced circumferential passageways closed at the inner periphery and having at the middle an annular chamber open at the inner periphery and adapted to receive air from the middle of said rotatable member, means at one side of said frame and core for conducting air from said annular chamber to said circumferential passage.

ways, said frame being provided with exhaust openings communicating with said circumferential passageways.

9. In a dynamo-electric machine, a rotatable member having a fan intermediate its ends, a stationary member comprising a frame and a core having spaced circumferential ventilating passageways, said stationary member having intermediate its ends an 10 annular chamber which surrounds the fan and is adapted to receive air from the latter and having at its bottom a chamber which communicates with said annular chamber and with the circumferential passageways 15 and said frame having an exhaust opening, whereby air will be forced by said fan into the annular chamber, thence into said second named chamber, thence through the passageways of the core and thence out through 20 the exhaust opening.

10. In a dynamo-electric machine, a rotatable field core divided into two substantially equal parts, a ventilating fan between said parts, a stationary armature provided 25 with a plurality of circumferential slots and being divided into two substantially equal parts, and an air receiving chamber between said two parts, said chamber communicating with all the slots in said stationary armature.

30 11. In a dynamo-electric machine, a rotatable field core provided with ventilating passageways, a fan at the middle of said field core, a stationary armature provided with parallel ventilating passageways and an air 35 conveying conduit dividing said member into two substantially equal parts, an air receiving chamber communicating with all said parallel ventilating passageways in said stationary member, and means for directing 40 the air from said fan to said air chamber.

12. In a dynamo-electric machine, a rotatable field member provided with ventilating radial and axial passageways, said field core being divided into two substantially 45 equal spaced parts, a fan between said spaced parts, a stationary armature provided with circumferential ventilating passageways, said stationary armature being divided into two substantially equal spaced 50 parts, a frame surrounding said armature and forming a circumferential conduit for receiving air from said fan, and means for directing air from said conduit to said ventilating passageways in said armature.

55 13. In a dynamo-electric machine, a rotatable member having a fan midway its ends and provided with ventilating passageways which lead to said fan from both directions, a laminated stationary member, a surrounding frame, said laminæ being spaced apart so as to form parallel radial ventilating passageways, said stationary member being divided into two spaced parts so as to form with said frame a circumferential air chamber surrounding said fan, and means for di-

recting the air from the chamber to the ventilating passageways at the periphery and at one side of the stationary member, said frame being provided at the opposite side with openings for the escape of the air. 70

14. In a dynamo-electric machine, a rotatable member, a ventilating fan at the center of said member, and a stationary member provided with circumferential ventilating passageways which communicate 75 only with the fan at one side of the machine and exhaust openings at the other side of the machine.

15. In a dynamo-electric machine, a rotatable member having a fan at the middle 80 thereof, and a stationary member having a central annular chamber adapted to receive air from the fan, said stationary member comprising a core having spaced circumferential ventilating passageways which 85 communicate with the annular chamber whereby air may pass from the latter through said passageways, the air entering and leaving the passageways at the outer periphery of the core. 90

16. In a dynamo-electric machine, a rotatable member provided at its middle with a ventilating fan, a surrounding stationary member having a plurality of circumferential ventilating passageways open at their 95 outer, but closed at their inner peripheries, and means for conveying air from said fan to said ventilating passageways.

17. In a dynamo-electric machine, a rotatable member having air passageways, and at its middle a ventilating fan, a stationary member surrounding the rotatable member, and having a plurality of circumferential ventilating passageways extending from the outer periphery toward but not entirely to 105 the air-gap of the machine, and means for conveying air from said fan through said passageways in the stationary member.

18. In a dynamo-electric machine, a rotatable member having ventilating passageways and at its middle a ventilating fan, a stationary member provided with circumferential ventilating passageways, and provided at its middle with a wide circumferential air receiving chamber, means for conveying the air from said chamber to the circumferential ventilating passageways and through the same without entering the air-gap between the rotatable and stationary members. 110 115

19. In a dynamo-electric machine, a rotatable member having at the middle a ventilating fan, a stationary member comprising a frame and a core having spaced circumferential ventilating passageways open 125 at the outer periphery of the core and closed at the inner periphery thereof, said stationary member having a central annular chamber which surrounds the fan and is adapted to receive air therefrom, and said stationary 130

member having at one side of the core means for conducting air from the annular chamber to said ventilating passageways and at the opposite side of the core exhaust openings.

20. In a high-speed turbo-generator, a rotatable laminated field member provided with axial and radial air passageways, the core of said field member being divided into
- 10 two substantially equal, spaced parts, a fan between said parts, a laminated stationary armature surrounding said field member and being provided with parallel circumferential ventilating passageways closed at their inner
- 15 peripheries, a frame surrounding said stationary member, the core of said armature being composed of two substantially equal spaced parts forming with the frame a wide circumferential air conduit, an air chamber
- 20 at one side of said armature core and with which all the ventilating passageways in the armature communicate, means for directing air from said conduit to said air chamber, and escape openings at the opposite side
- 25 of said frame, whereby the air passes uni-

formly and freely in parallel planes from one side of said armature to the other.

21. In a dynamo-electric machine, a rotatable member having ventilating passageways arranged at intervals for the outward flow of air due to the rotation of said member, and having at the center a passageway through which a greater flow of air takes place than takes place through the remaining passageways, a stationary member provided with ventilating passageways arranged at intervals and provided at the center with an annular chamber for receiving the air from the center of the rotatable member, said annular chamber communicating with all of said ventilating passageways in the stationary member whereby air may pass from said chamber through all said passageways.

In testimony whereof I affix my signature, 45 in the presence of two witnesses.

BERNARD ARTHUR BEHREND.
